UNITED STATES PATENT OFFICE

2,085,254

FRIT KILN

Joseph William Emery, Cobridge, England

Application September 12, 1936, Serial No. 100,444
In Great Britain February 15, 1936

1 Claim. (Cl. 263—15)

The present invention has relation to a frit kiln and has for its object to generally increase the utility, efficiency, and expediency of such a kiln whereby an increased output is rendered possible from a kiln of given size, and facilities are provided for change of colour, repair, cleaning and the like.

According to the present invention there is provided a frit kiln comprising in combination a box-like heating chamber, a truck adapted to be wheeled therein, a recess in the upper peripheral edge of the truck, a horizontal protruding flange in the upper area of the chamber co-operable with said recess, a forwardly and rearwardly extending recuperator flue system at the upper part of the chamber, an air supply pipe for supplying heated air to the burner at the rear of the chamber, and which passes longitudinally through the upper part of the recuperator flue and openings 5 in the lower part of the wall of the chamber beneath the protruding flange for the passage of air into the lower part of said chamber.

In order that this invention may be clearly understood and readily carried into practice, reference may be had to the appended explanatory sheets of drawings, upon which:—

Figure 1 illustrates the frit kiln in longitudinal sectional elevation, and

Figure 2 in vertical sectional elevation.

In a convenient embodiment of the present invention the kiln or chamber is constructed of three brick walls to a box-like formation, being two side walls a_1 , a^1 and a rear wall a^2 , an arched roof or top a^3 being employed. It will be noted that the front of the chamber a_1 , a^1 , a^2 , a^3 is open for the purpose of the reception of a wheeled truck b^1 . The body of the truck, indicated by the reference letter b , is of metal but the said truck is lined internally with refractory slabs 30 b^2 which are spaced from the metal by means of flint or other heat-resisting material b^3 . Provided in the upper part of the chamber are protruding flanges a^4 around the sides and rear, and it will be noted that at b^4 the refractory brick-work of the truck is recessed to accommodate 35 said flanges a^4 . At the front of the truck a platform b^5 is provided having a covering of fire brick or the like b^6 and means b^7 for the manipulation of the truck. This truck is provided with 40 a sealing medium, such as clay, sand and water, or the like at the part b^4 , and it will be appreciated that when the truck is pushed home into the chamber a seal is effected between b^4 and a^4 at the sides and rear of the chamber. At the 45 front of the chamber the truck is adapted to be

sealed as for instance at the opening a^5 by that opening being filled with bricks, clay and the like. b^8 is an outlet for the frit which may be normally plugged, and a^6 represents the openings in the wall of the chamber to permit of the passage of air for cooling the lower part of the chamber and the truck, it being appreciated that the heating is effected within the truck and beneath the top a^3 of the chamber. To this end the chamber at its rear a^7 is open for the reception of an oil or gas burner or other like heating device c . a^8 is a horizontal return flue connecting by a^9 to a recuperator a^{10} which in turn connects with a chimney or outlet a^{11} . c^1 is the secondary air supply pipe connected at the front extremity to an electric blower or like device c^2 and at the rear extremity terminating in a nozzle or like device c^3 adjacent the burner c .

In operation it will be appreciated that the truck is normally filled with the materials to be fritted and the sealing material placed about the ledge b^4 . The truck is then pushed home into the chamber and the seal effected between b^4 and a^4 . Following this operation the opening a^5 is bricked up. The oil burner is then ignited and the heat and products of combustion caused to pass into the interior of the truck and the upper part of the chamber, whence they flow away by means of the flue a^8 and passages a^9 , a^{10} and a^{11} , the secondary air being supplied by way of c^1 , c^2 , c^3 which 50 secondary air is heated by its recuperator a^{10} . The truck may operate on rails (not shown).

It will be appreciated that in this invention more than one truck may be utilized with the same kiln, so that different coloured glazes may be 35 expeditiously constituted. Further all parts of the kiln and trucks are readily accessible for repair, cleaning, etc.

What I claim as my invention and desire to secure by Letters Patent is:—

A frit kiln comprising in combination a box-like heating chamber, a truck adapted to be wheeled therein, a recess in the upper peripheral edge of the truck, a horizontal protruding flange in the upper area of the chamber co-operable with 45 said recess, a forwardly and rearwardly extending recuperator flue system at the upper part of the chamber, an air supply pipe for supplying heated air to the burner at the rear of the chamber, and which passes longitudinally through the upper 50 part of the recuperator flue and openings in the lower part of the wall of the chamber beneath the protruding flange for the passage of air into the lower part of said chamber.

JOSEPH WILLIAM EMERY. 55
